(57) **CLAIM**

The ornamental design for a carrier pocket for longitudinally compressed tablet, as shown.

DESCRIPTION

FIG. 1 is a perspective view of a carrier pocket for longitudinally compressed tablet according to a second embodiment showing my new ornamental design;

FIG. 2 is a top view thereof; and,

FIG. 3 is a right side view.

The broken line in the figure drawings represents unclaimed portions of a carrier pocket for longitudinally compressed tablet that form no parts of the claimed design.
